(57) **CLAIM**

The ornamental design for an electronic display assembly structure, as shown and described.

DESCRIPTION

FIG. 1 is a front perspective view of an electronic display assembly structure;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view thereof, shown in an environmental state of use.

The broken lines showing a graphical interface on the display surface in FIG. 8 depict unclaimed environment only and form no part of the claim, while all other broken lines seen in the drawings depict portions of the electronic display assembly structure that form no part of the claimed design.
